UNITED STATES PATENT OFFICE.

ANDREW G. ROBERTSON, OF AUBURN, NEW YORK.

WOVEN PILE FABRIC.

No. 908,888.

Specification of Letters Patent.

Patented Jan. 5, 1909.

Application filed May 21, 1908. Serial No. 434,066.

To all whom it may concern:

Be it known that I, ANDREW G. ROBERTSON, a citizen of the United States, residing at Auburn, in the county of Cayuga and State of New York, have invented certain new and useful Improvements in Woven Pile Fabrics, of which the following is a specification.

My invention relates to woven pile fabric such as that used in the manufacture of wilton, brussels and velvet carpets.

My invention particularly relates to that class of fabric in which the pile loops are formed by the pile warp threads being passed over pile wires which are arranged, in the loom, parallel with the said pile warp threads. The said pile loops are bound in by filling or weft threads which are held by the binder warp threads, and the pile loops are then cut to produce wilton or velvet carpets.

The object of my invention is to provide a novel method of securing the pile loops so that they will not become loose and pull out. This trouble was due to the fact that the filling threads holding said loops were slightly separated by the crossing of the binder warp threads, which would leave one side or end of the pile loops unbound, so that it would not stand up straight and would easily pull out.

In my improved fabric the pile warp thread is held by two filling threads, one in each shed, at the point where the binder warp threads cross and I dispense with the loose ends of the pile warp loops at the points where there is no filling thread next to it to hold said ends securely and in an upright position.

Referring to the drawings: Figure 1. is a longitudinal section of my improved woven pile fabric, drawn on an enlarged scale, showing the pile wire and the pile loops uncut; Fig. 2. is a similar view showing the pile threads after they have been cut.

In the drawings A and B are the binder warp threads and C is the stuffer warp thread. The latter is used to give the fabric a heavier body. The upper filling or weft threads 1, 2 and 3 are arranged above the stuffer warp thread C and the lower filling threads 6 and 7 are arranged below the said stuffer warp thread C. The binder warp threads cross at the points 10, 11, 12 and 13, and form the sheds 20, 21, 22 and 23, each

of which embraces the three upper filling threads 1, 2 and 3, and the two lower filling threads 6 and 7.

The pile warp thread D is held in the body of the fabric by the filling threads and the pile loops are formed by raising the pile warp thread D up from the body of the fabric and passing it over the pile wire E and securing it with the filling thread 2, thus one pile loop is formed. The pile warp thread D is again passed over the pile wire E and secured by the filling thread 3, and another loop formed. The lower filling threads are inserted in their proper order and the binder warp threads crossed to complete one shed.

When the pile loops are cut by the knife F, on the pile wire E, each shed will contain four ends or tufts of pile threads, as shown in Fig. 2. Each end or tuft of the pile warp will be securely held in an upright position, due to the fact that there is a filling thread on each side of said end or tuft to support the latter, and also securely hold the same in the body of the fabric.

After the shed is completed the pile warp thread D is not raised from the body of the fabric to form another tuft until the filling thread 1 of the next succeeding shed has been inserted. Said pile warp thread is then raised and passed over the pile wire and the loops formed as above described.

When the fabric is beaten together and the loops of pile warp thread are cut, the loose ends or tufts d' and d will be firmly held between the filling threads 1 and 2. The ends d² and d³ of the pile threads will be firmly held between the filling threads 2 and 3. The loop of pile warp forming the ends of tufts d and d³ extends from one shed to the next succeeding shed and said loop is secured by the two filling threads 1 and 3, one in each shed. The loop of pile warp, forming the ends d' and d², is held by the filling thread 2.

There are no loose ends of pile threads between the filling threads 1 and 3 at the point where the binder warp threads A and B cross. It will be seen that each loose end is firmly bound in the body of the fabric and will be held in an upright position due to the fact that there is a filling thread on each side of the end or tuft. By using three upper filling threads and two lower filling threads in each shed a greater tension is made on the binder warp thread at the top of the shed which

will cause the upper filling threads to be drawn tightly together and securely hold the pile loops in place.

Any number of frames may be used in carrying out my invention so that different colors of pile warp threads may be used in manufacturing the fabric.

Having thus described my invention I claim and desire to secure by Letters Patent.

16 1. In a woven pile fabric, the combination of upper and lower filling threads, pile warp threads, binder warp threads, said binder warp threads crossed to form sheds, a loop formed of said pile warp threads, said loop held by an upper filling thread in one shed and by an upper filling thread in the next adjoining shed and another loop held by an upper filling thread in the center of said shed.

20 2. In a woven pile fabric, the combination of upper and lower filling threads, pile warp threads, binder warp threads crossed to form sheds to embrace said filling threads, a pile warp thread bound in one shed and having a standing end between two of said upper filling threads of the next adjoining shed and a pile warp thread bound by an upper filling thread in the center of said shed having standing ends on each side of said last mentioned filling thread.

30 3. In a woven pile fabric, the combination of upper and lower filling threads, pile warp threads, binder warp threads, said binder warp threads crossed to form sheds to embrace five of said filling threads, a plurality of loops formed of said pile warp threads in each shed and having standing ends, said ends held upright by a filling thread on each side of the same, said pile thread forming the loop at the

ends of each shed being bound in the next adjoining shed.

40

4. In a woven pile fabric, the combination of upper and lower filling threads, pile warp threads, binder warp threads crossed to form sheds, said sheds containing three upper filling threads, a loop formed of said pile thread held by the upper filling thread in the center of said shed, and a loop of said pile thread held by the upper filling thread at the end of one shed and by the upper filling thread at the end of the next adjoining shed.

45

5. In a woven pile fabric, the combination of upper and lower filling threads, pile warp threads, binder warp threads crossed to form sheds, said sheds containing three upper filling threads and two lower filling threads, a loop formed of said pile thread held by the upper filling thread in the center of said shed, and a loop of said pile thread held by the upper filling thread at the end of one shed and by the upper filling thread at the end of the next adjoining shed.

50

6. In a woven pile fabric, the combination of upper and lower filling threads, pile warp threads, binder warp threads crossed to form sheds, said sheds containing three upper filling threads and two lower filling threads, said pile warp threads cut to form four standing tufts in each shed and said pile warp tufts held by said upper filling threads.

55

In testimony whereof I affix my signature 70 in presence of two witnesses:

ANDREW G. ROBERTSON.
